(57) **CLAIM**

The ornamental design for a remote control, as shown and described.

DESCRIPTION

FIG. 1 is a top, front and side perspective view of a remote control embodying my new design.

FIG. 2 is a bottom, front and side perspective view thereof.

FIG. 3 is a top view thereof.

FIG. 4 is a bottom view thereof.

FIG. 5 is a first side view thereof, the opposite side being a mirror image with the exception of the unclaimed logo.

FIG. 6 is a front view thereof.

FIG. 7 is a back view thereof.

FIG. 8 is a top, front and side perspective view thereof showing an environment of the remote control with an unclaimed wrist strap; and,

FIG. 9 is a bottom, front and side perspective view thereof. The broken lines, where shown, are for illustrative purposes only and form no part of the claimed design. The wrist strap shown in broken lines in FIGS. 8 and 9 illustrates one use and environment of the remote and forms no part of the claimed design.
